UNITED STATES PATENT OFFICE.

CLAUDE E. PRICE, OF SPOKANE, WASHINGTON.

DESIGN FOR A CANDY-BOX.

58,449.

Specification for Design.

Patented July 19, 1921.

Application filed July 2, 1919. Serial No. 308,336. Term of patent 14 years.

To all whom it may concern:

Be it known that I, CLAUDE E. PRICE, a citizen of the United States, residing at Spokane, in the county of Spokane and State of Washington, have invented a new, original, and ornamental Design for a Candy-Box, as shown in the accompanying drawings in the following specification.

The invention consists of a design for a box which is illustrated on the accompanying drawings, wherein;

Figure 1 is a perspective of the complete and assembled box.

Fig. 2 is an end view.

I claim:

The ornamental design for a candy box as shown.

CLAUDE E. PRICE.
